(57) CLAIM

The ornamental design for a case for stick foundation, as shown and described.

DESCRIPTION

FIG. 1 is a perspective view of a case for stick foundation showing our new design;

FIG. 2 is a front view thereof, a rear view being the same as the front view;

FIG. 3 is a right side view thereof, a left side view being the same as the right side view;

FIG. 4 is a plan view thereof;

FIG. 5 is a bottom view thereof; and,

FIG. 6 is a front view without a cap thereof.

For convenience of illustration, the main member of the case for stick foundation is disclosed separately.
